UNITED STATES PATENT OFFICE

JOHN A. H. SIERS, OF JERSEY CITY, NEW JERSEY

HAIR WAVING DEVICE

Application filed January 10, 1931. Serial No. 507,769.

This invention relates to hair waving devices, and has for its general object and purpose to provide an easily operated device for waving the hair with rapidity, and a minimum of inconvenience.

It is another important object of the invention to provide a hand operated hair waving device for easily and quickly producing what is generally referred to as "permanent" waves in the human hair.

It is a more particular object of the invention to provide means in a device of this kind for automatically first forming the waves in the hair before maximum pressure is applied thereto, and which may be used in connection with means for vaporizing a solution such as that generally employed in the process of permanently waving the hair.

It is a more specific object of my invention to provide a hair waving device which embodies two vertically movable sections, one of which is provided with longitudinally extending grooves and the other with complementary ribs whereby the hair is pressed into said grooves when the two sections are brought together, in combination with movable comb members carried by one of said sections and actuating means therefor carried by the other section whereby the hair is arranged in a wave formation across said grooves before maximum pressure is applied thereto.

It is also an additional object of the invention to provide improved means for mounting the comb members and distributing the vapor through said comb members together with simple and positively operating means for relatively moving or shifting the comb members in pairs in opposite directions.

It is a further general object of my invention to provide a hair waving device as above characterized, and which is relatively simple in its construction, highly effective and reliable in practical use, and capable of manufacture at comparatively small cost.

With the above and other objects in view, the invention consists in the improved hair waving device, and in the form, construction and relative arrangement of its several parts, as will be hereinafter more fully described,

illustrated in the accompanying drawings, and subsequently incorporated in the subjoined claims.

In the drawings, wherein I have disclosed one simple and practical embodiment of my invention, and in which similar reference characters designate corresponding parts throughout the several views,

Fig. 1 is a side elevation of a practical embodiment of my improved hair waving device, showing the pressure applying members in spaced apart open position;

Fig. 2 is a bottom plan view, the movable members being in closed position;

Fig. 3 is an end elevation;

Fig. 4 is a longitudinal sectional view taken substantially on the lines 4—4 as indicated in Figs. 2 and 5;

Fig. 5 is a top plan view of the lower section of the device as indicated by the line 5—5 in Fig. 4;

Fig. 6 is a transverse sectional view taken on the line 6—6 of Fig. 1;

Fig. 7 is a detail fragmentary bottom plan view of the upper section of the device as indicated by the line 7—7 in Fig. 1;

Fig. 8 is a transverse sectional view on an enlarged scale showing the action of the pressure applying devices upon the hair just prior to the relative shifting movement of the comb members;

Fig. 9 is a fragmentary side elevation on an enlarged scale of one of the comb members;

Fig. 10 is an end elevation thereof;

Fig. 11 is a transverse sectional view taken on the line 11—11 of Fig. 9, and

Fig. 12 is a detail perspective view of one of the operating cams for the comb members.

Referring in detail to the drawings, 5 and 6 generally designate the upper and lower hair pressing members respectively. Each of these members is provided at one of its ends with an internally threaded boss or extension 7, and with these extensions the threaded ends of the hollow or tubular handle members 8 are connected.

Each of the handle members 8 at its inner side and in longitudinally spaced relation from the ends of the sections 5 and 6 of the device is formed with a longitudinally elongated

gated lug or projection 9 having a slot 10 therein.

At each side of the device, a pair of links 11 operatively connects the upper and lower sections 5 and 6 with the lower and upper handle members 8. Each of these links has an end portion 12, said end portions being offset in relatively opposite directions from the central portion 13 of the link. These central portions of the links at each side of the device are connected by the bolt 14 and the spacing collar 15, said spacing collar having reduced end portions upon which the inner link of each pair may freely pivot while the outer link has pivotal movement upon the bolt 14, as clearly seen in Fig. 5 of the drawings. The forward ends of the links in each pair are respectively pivotally connected as at 16 with the rear ends of the sections 5 and 6. The rear ends of the links in each pair which are connected with the upper section 5 are connected by the transverse bolt 17 which has sliding movement in the slot 10 of the lug 9 on the lower handle member 8, while the other links connected with the lower section 6 are similarly connected at their rear ends by the bolt 18 having sliding movement in the slot 10 of the lug 9 on the upper handle member 8. The lower section 6 of the device at its rear end is provided with the transversely spaced upwardly extending posts or rods 19 which are loosely engaged through correspondingly located openings in the rear end of the upper section 5. Thus as the handle members 8 are moved towards and from each other, through the link connections 11, the sections 5 and 6 are guided by the posts or rods 19 so that they will be moved accurately in a straight vertical line. When these sections are spaced apart as in Fig. 1 of the drawings, the bolts 17 and 18 are positioned in the forward ends of the slots 10, and as the handle members are brought together, said bolts move rearwardly in the slots 10 as the rear ends of the links 11 approach each other, as seen in Fig. 4 of the drawings.

The upper section 5 of the device is provided on its under side with spaced parallel longitudinally extending ribs 20 having convex surfaces, each of which at the center of the rib is transversely toothed or serrated as shown at 21. In line with these ribs, the bores 22 are formed through the section 5 to receive the parallel legs or arms 24 of a suitable electric resistance unit 23, which is of elongated U-shaped form, the intermediate part of said resistance unit at the rear end of the section 5 extending transversely between the legs 24. Since this resistance unit however, might be of various different types or constructions, I have not specifically illustrated herein any particular means for mounting or securing the same in fixed relation to the section 5 of the device. Electric current is supplied

thereto through the wires 26 extending through the upper handle member 8.

At the outer sides of the respective ribs 20 and between the same, the section 5 of the device is further provided with the longitudinally extending rectangular channels 27, the purpose of which will be presently explained.

The lower section 6 of the device is provided in its lower portion with the chamber 28 communicating at its rear end with the extension 7 and the hollow handle member 8. The lower side of this chamber is closed by the removable bottom plate 29 and within said chamber an electrical resistance unit indicated at 30 of any preferred type is arranged. The body of the section 6 above the chamber 28 is provided therein with a plurality of vertical ducts 31 communicating at their upper ends with each of the longitudinally extending grooves 32 which are formed in the upper surface of said section in line with the ribs 20 on the upper section 5 of the device.

Between the grooves 21, the lower section 6 is formed with a wide longitudinally extending channel 33 and at the outer side of each of said grooves, with a relatively narrow longitudinal channel 34. The central channel 33 receives the relatively slidable comb members 35 and 36 respectively. The comb member 36 is comparatively thick and occupies somewhat more than one-half of the channel 33. A similar comb member 37 is also mounted in each of the outer channels 34. The teeth 38 of the several comb members project above the upper surface of the section 6, and each of the comb members 36 and 37 is provided with vertical passages 39 therethrough opening at their upper ends between the teeth 38 of said comb members and communicating at their lower ends with a longitudinal groove 40 in the lower edge of each comb member. Relatively short ducts 41 afford communication between the chamber 28 and each of the grooves 40.

One end of each comb member has its lower portion cut away as indicated at 42 to accommodate an expansion spring 43 which yieldingly holds the comb in a normal position. The other end of the relatively thick comb member 36 is also cut away or recessed on one side thereof as shown at 44 to accommodate the spring 43 which acts upon the adjacent comb member 45. From reference to Fig. 5 of the drawings, it will be readily understood that the springs 43 act to yieldingly resist longitudinal movement of one of the comb members 37 and the comb member 35 in one direction while movement of the other comb member 37 and the member 36 is resisted in the opposite direction.

Each comb member is provided in spaced relation to its opposite ends and near its lower edge with longitudinally extending slots 45

to receive transverse locking rods 46 which retain said comb members within the channels of the section 6. These locking rods may be inserted through threaded openings 5 at either side of the section 6, which openings are closed by means of the screws or plugs 47.

Current is supplied to the resistance unit 30 by the wires 48 also extending from the handle member 8 and through an opening 49 10 therein exteriorly of the handle member and through a suitable opening provided in the rear end of the section 6.

A solution may be conveniently supplied to the chamber 28 through the lower hollow handle member 8 connected therewith, the open rear end of said handle member being then closed by the threaded plug 50. The current supply wires 48 are connected with a suitable rheostat for controlling the temperature of the resistance unit 30 independently of the resistance unit 23, since the solution vaporizes at a temperature of approximately 196° F. whereas, it is desirable that the temperature of the upper section 6 of the device 20 be maintained at about 200° F. so as to prevent any condensation of the vapor rising through the ducts and passages in the lower section 6 and the comb members into contact with the hair and the upper section 5 of the device. 25

The rear end of each of the comb members is further provided in the upper edge thereof with an inverted V-shaped notch or recess 51, upon one edge of which a wear plate 52 is 30 suitably secured. It will be evident of course, that these notches or recesses in the oppositely shifting pairs of comb members are out of alignment with each other. Correspondingly located operating cams 53 are carried 40 by the upper section 6, each of said cams being of substantially V-shape form and having an integrally formed stud or pin 54 serving as a rivet whereby the cam member may be rigidly and permanently secured to the 45 rear end of the section 5 of the device. These cam members are located within the slots 27.

In the use of the device as above described, the solution with which the hair is to be treated, is supplied to the chamber 28 through the 50 handle member 8 and is converted into a vaporous condition by heat from the electrode 30, while the upper section 5 of the device is highly heated by the electrode 23. With the two sections 5 and 6 in the open position 55 shown in Fig. 1, the hair is now placed between said sections across the lower section 6 and upon the upstanding teeth of the comb members 37, 35 and 36. The rear ends of the two handle members 8 are now pressed together so that through the link connections 11, the upper section 5 will be lowered, and the lower section 6 correspondingly raised. The ribs 20 of the upper section 5 as they enter between the upstanding teeth of the 60 spaced pairs of comb members, engage upon

the hair forcing the same downwardly into the grooves 32 of the lower section 6 so that the teeth or serrations 21 of said ribs engage and grip the uppermost strands of hair, before there is any contact of the cams 53 with the rear ends of the respective comb members. Upon further relative movement of the sections 5 and 6 towards each other from substantially the position shown in Fig. 8 of the drawings, the cam members 53 engage upon the wear plates 52 on the rear ends of the combs, and enter the recesses 51, such camming action shifting the pairs of combs 37, 35 and 37, 36 respectively, in relatively opposite directions against the expansive pressure of springs 43 to substantially the positions shown in Fig. 5 of the drawings. The hair is thereby caused to assume a waved form or condition as further pressure is applied thereto by the ribs 20. As the waved hair is held under compression within the grooves 32 of the section 6, the vapor rising through the ducts 31 and 41 into grooves 32 and through the passages 39 of the comb members from chamber 28, thoroughly permeates the hair and by its chemical action thereon, causes the hair to assume a more or less permanent set so that upon the release of the pressure, the hair strands will not return to their originally straight or unwaved condition. After the hair has been subjected to pressure and the action of the vapor for the necessary length of time, the two handle members 8 are separated so as to thus vertically separate the sections 5 and 6 and permit the waved hair to be removed. In this manner, the hair over the entire head may be quickly treated and provided with a permanent wave. 95

If instead of a permanent wave in the hair, it is desired to provide a Marcel wave, the oil vapor is not used, but the hair is merely subjected to heat and pressure between the upper and lower sections 5 and 6 of the device. Of course, the combs will be operated in the manner above described to first produce the waved condition in the hair before the maximum pressure is applied thereto. 100

From the foregoing, it will be seen that I have devised a very simply constructed and efficiently operating hair waving device, the novel feature of which is essentially characterized by the provision of movable means on one of the presser members for producing a waved formation of the hair prior to the application of maximum pressure thereto so that when the hair is compressed within the longitudinal grooves, waves or curves of definite arc lengths will be formed in the hair. Also by the provision of means carried by one of the presser members for vaporizing the chemical solution and applying the vapor to the hair while under pressure, the permanency of the hair waves is assured. 115 120 125 130

The essential parts of the device may be readily fabricated from aluminum or other relatively light composition metal so that the device may be easily handled and applied to various parts of the head. I have herein illustrated and described, a mechanical embodiment of my present improvements, which is thought to be entirely practical for the purpose in view. It will however, be evident that insofar as the detail structural features of the elements and their arrangement and relative proportions are concerned, various modifications might be resorted to. Accordingly, I reserve the privilege of adopting all such structural changes as may hereafter be found advisable and as may be fairly considered within the spirit and scope of the appended claims.

I claim:

1. A hair waving device comprising complementary presser members, means slidably connecting said members with each other, operating handles therefor, and relatively movable means connecting each handle to one of the presser members to impart a rectilinear movement to the presser members towards and from each other upon the operation of said handles.

2. A hair waving device comprising complementary presser members, operating handles therefor, relatively movable means connecting each handle to one of the presser members to impart a rectilinear movement to the presser members towards and from each other upon the operation of said handles, relatively movable hair engaging means carried by one of said members, and means directly coacting with said hair engaging means to actuate the latter as the presser members move towards each other to produce a waved formation in the hair prior to the application of maximum pressure thereto.

3. A hair waving device comprising complementary presser members and means for moving the same towards and from each other, relatively movable hair engaging means carried by one of said presser members, and means carried by the other presser member directly coacting with said relatively movable means as the presser members are moved towards each other to actuate said means and produce a waved formation in the hair prior to the application of maximum pressure thereto.

4. A hair waving device comprising complementary presser members and means for moving the same towards and from each other, a plurality of relatively movable hair engaging combs carried by one of said members, means yieldingly holding the respective combs in a normal position, and cam means coacting with said combs as the presser members are moved towards each other to shift the combs in relatively opposite directions and produce a waved formation in

the hair prior to the application of maximum pressure thereto.

5. A hair waving device comprising complementary presser members of elongated form, one of said members having longitudinally extending grooves and the other member having ribs thereon to be received in said grooves, hair engaging means carried by one of said members and longitudinally movable with respect thereto, and means carried by the other member directly coacting with said hair engaging means to produce a waved formation of the hair extending at right angles to said grooves prior to the application of maximum pressure to the hair.

6. A hair waving device comprising complementary presser members of elongated form, one of said members having longitudinally extending grooves and the other member having ribs thereon to be received in said grooves, hair engaging means carried by one of said members and longitudinally movable with respect thereto, and means carried by the other of said presser members to engage and automatically actuate said movable means and produce a waved formation in the hair extending at right angles to said grooves prior to the application of maximum pressure to the hair.

7. A hair waving device comprising complementary presser members between which the hair is adapted to be arranged, means carried by said members for producing a waved formation of the hair prior to the application of maximum pressure thereto, one of said members being provided with means for supplying a chemical vapor to the hair, and means for heating the other of said members.

8. A hair waving device comprising complementary presser members between which the hair is adapted to be arranged, means carried by said members for producing a waved formation of the hair prior to the application of maximum pressure thereto, one of said members having a chamber therein to receive a chemical solution and ducts communicating with said chamber for supplying vapor to the hair, heating means within said chamber for vaporizing the chemical solution, and separate heating means for the other of the presser members.

9. A hair waving device comprising complementary elongated presser members provided upon their opposed faces with cooperating longitudinally extending ribs and grooves respectively, the ribs having serrated surfaces to engage and hold the hair positioned across said grooves, and coacting means carried by said members including relatively movable hair engaging combs on one of said members to produce a waved formation in the hair after engagement of the serrated surfaces of the ribs therewith and prior to the application of maximum pressure to the hair.

10. A hair waving device comprising complementary elongated presser members provided upon their opposed faces with cooperating longitudinally extending ribs and grooves respectively, the ribs having serrated surfaces to engage and hold the hair positioned across said grooves, coacting means carried by said members including relatively movable hair engaging combs on one of said members to produce a waved formation in the hair after engagement of the serrated surfaces of the ribs therewith and prior to the application of maximum pressure to the hair, said grooved presser member having means for supplying a chemical vapor to said grooves for contact with the hair, and means for heating the other presser member.

11. A hair waving device comprising complementary elongated presser members provided upon their opposed faces with cooperating longitudinally extending ribs and grooves respectively, the ribs having serrated surfaces to engage and hold the hair positioned across said grooves, coacting means carried by said members including relatively movable hair engaging combs on one of said members to produce a waved formation in the hair after engagement of the serrated surfaces of the ribs therewith and prior to the application of maximum pressure to the hair, said grooved presser member having a chamber to receive a chemical solution and ducts extending from said chamber to each of said grooves, means for vaporizing the solution in said chamber, and separate heating means for the other presser members.

12. A hair waving device comprising complementary presser members and coacting means thereon guiding said members for relative rectilinear movement towards and from each other, relatively slidable comb members carried by one of the presser members, and means cooperatively engaging said comb members at one of their ends automatically sliding said members in relatively opposite directions as the presser members are moved towards each other to closed position upon the hair.

13. In a hair waving device, complementary presser members movable towards and from each other, relatively slidable hair engaging combs carried by one of said members, and cam means carried by the other member coacting with means on one end of each comb member to slide said comb members in relatively opposite directions as the presser members are moved towards each other to closed position upon the hair.

14. In a hair waving device, complementary presser members movable towards and from each other, and means carried by said members for simultaneously heating and supplying a chemical vapor to the hair arranged therebetween.

15. In a hair waving device, complementary presser members movable towards and from each other, and means carried by one of said members for supplying a chemical vapor to the hair arranged therebetween.

In testimony that I claim the foregoing as my invention, I have signed my name hereto.

JOHN A. H. SIERS.
